United States Patent

Des. 235,713
Patented July 8, 1975

235,713

BED HEADBOARD

Aaron Donner, Weston, Conn., assignor to
The Lane Company, Inc.

Filed July 10, 1974, Ser. No. 487,378

Term of patent 14 years

Int. Cl. D6—01

U.S. Cl. D6—79

The figure is a front, top and left side perspective view of a bed headboard showing my new design.

The rear of the headboard is plain and unornamented.

I claim:

The ornamental design for a bed headboard, as shown and described.
